HARRY A. FOOTHORAP, OF HARRISBURG, PENNSYLVANIA, ASSIGNOR TO ELLIOTT-FISHER COMPANY, OF HARRISBURG, PENNSYLVANIA, A CORPORATION OF DELAWARE.

REGISTER-LOCK.

1,243,277.

Specification of Letters Patent. Patented Oct. 16, 1917.

Application filed February 6, 1911. Serial No. 606,930.

To all whom it may concern:

Be it known that I, HARRY A. FOOTHORAP, a citizen of the United States of America, residing at Harrisburg, in the county of 5 Dauphin and State of Pennsylvania, have invented certain new and useful Improvements in Register-Locks, of which the following is a specification.

This invention relates to register locks 10 for writing-adding machines and has for its object to provide a simple and effective lock whereby the register of a writing-adding machine may be readily attached to or detached from the register supporting bar 15 and quickly adjusted either to a new position on the bar or in such slight degrees as may be necessary to cause a proper alinement of the register and its operating mechanism.

20 In the accompanying drawings—

Figure 1 is a perspective view of a register base equipped with my improved lock and attached to the register supporting bar, the major portion of the register being indicated in dotted lines.

Fig. 2 is a plan view of the subject-matter of Fig. 1.

Fig. 3 is a longitudinal sectional view through the register base and lock, the unlocked or retracted position of the register bar being indicated in dotted lines.

Fig. 4 is a similar section showing the locking bar retracted and the base in the act of removal from the register bar.

35 Fig. 5 is a transverse section on the line 5—5 of Fig. 2.

Fig. 6 is a detail perspective view of the rack block and one of its supporting screws.

Fig. 7 is a detail perspective view of the 40 locking bar and its immediately associated parts detached.

Fig. 8 is a transverse section on the line 8—8 of Fig. 2, and

Fig. 9 is a sectional view showing the 45 manner in which the knurled head 24^b is locked to the locking bar 24.

1 indicates what is known in the art as a register supporting bar which ordinarily extends across the rear of the main frame 50 of a writing-adding machine, more particularly a machine of the Elliott-Fisher type. This bar is of dove-tailed form and is provided at the upper front corner thereof with a rack or series of teeth 2 which may 55 be and preferably are integral with the bar.

The bar 1 supports a register 3 which may be located at any point in the length of the bar and is ordinarily operated by a master wheel (not shown) mounted on the movable carriage of the machine and engaging 60 the number wheels of the register in a manner well understood in the art.

The register base 4 is cut to form a bar channel 5 which ordinarily conforms in shape to that of the bar, but in the present 65 instance has its side walls 6 and 7 inclined in the same direction. This form of the channel produces an undercut at one side thereof, but makes its entrance as wide as its bottom so that the register base may be 70 slipped over the bar at any point in its length instead of necessitating the removal of the base by slipping it along the bar to the end thereof, as usual.

In addition to the channel 5 which is 75 formed in the under side of the base 4, said base is provided with a cavity 8 opening through the top of the base adjacent to its front end and adapted for the reception of a rack block 9 having teeth 10 designed to 80 engage the rack 2 of the register bar. The block 9 is provided with trunnions 11 which extend into sockets 12 formed in the inner ends of a pair of bearing screws 13 screwed into horizontal openings 14 extending into 85 the cavity 8 from the opposite sides of the base, see Fig. 5. By means of the screws 13 slight lateral adjustment of the register 3 relative to the rack block 9 is permitted in order to facilitate the accurate alinement 90 of the register and its operating mechanism. This provision for slight adjustment of the block 9 obviates the necessity for absolute accuracy in cutting the teeth 2 on the register bar and this materially cheapens the cost 95 of production.

It is also desirable to allow slight play of the block 9 in order to accommodate any slight irregularities of the teeth and this condition is met by making the sockets 12 100 of sufficient dimensions and placing in rear of the block a leaf spring 15 seated against the wall of the recess 8 and tending to urge the block 9 rearwardly or toward the rack 2.

At the rear side of the register bar channel 5 the under side of the base is cut out to form a transversely dove-tailed longitudinal channel 16 for a dove-tailed locking bar 17. The bar 17 is mounted to slide longitudinally in the channel 16 and is provided 110

with an inclined end 18 designed to be urged against one side of the bar 1 to retain the register against vertical movement relative to the bar and to draw the rack block 9 into close engagement with the rack 2, it being understood of course that the toothed portion of the rack block extends into the cavity 5. The locking bar or slide 17 is permitted considerable longitudinal movement limited 10 by a stop pin 19 depending from the base 4 and accommodated in a longitudinal slot 20 in the upper side of the bar 17. The pin 19 also serves for the attachment of one end of a locking bar retracting spring 21, the 15 opposite end of which abuts against an element carried by the bar 17 and tends to move the bar to its retracted position, shown in Fig. 4.

In addition to this limited movement of 20 the locking bar which is intended to present it to or withdraw it from the register bar, it is desirable to provide means whereby, when the bar has been moved forward to its engaging position, said bar may be urged with great force, or cramped, securely 25 against the register bar to insure the rigid retention of the register thereon. For this purpose the bar 17 is provided adjacent to its rear end with a transverse cavity 22 designed to accommodate a wing 23 fixed to the inner end of a shaft 24 afforded a bearing in the bar 17 and provided beyond the rear end of said bar with a knurled head 24. The parts are so proportioned that the wing 30 23 may be turned down flush with or below the upper surface of the bar 17 so as to present no obstruction to the sliding movement of the latter. When, however, the locking bar is pushed forward into approximate 35 engagement with the register bar 1, the wing is brought under or opposite an inclined or cam slot 25 disposed transversely of the base, as clearly shown in Fig. 2. Since the wing 23 swings on an axis disposed longitudinally of the locking bar and since the cam slot 25 is disposed at a slight transverse angle, it is obvious that as the wing enters one end of the slot and travels toward the other, it must necessarily approach the front of the register and since the wing has no relative movement longitudinally of the locking bar, it is obvious 40 that this movement of the wing must be accommodated by an inward or forward movement of the bar. This further movement of the locking bar after it has been shoved against the register bar, produces the cramping or rigid locking action necessary to insure the absolutely rigid retention of the 45 register by its supporting bar.

Attention is now directed to the fact that while the rack block 9 and the locking bar 17 coact, each is useful independently of the other, since the locking bar alone constitutes an efficient form of clamp in con-

junction with the opposite wall of the channel 5 and the advantages of the rack block are not dependent upon the specific mechanism employed to draw said block into intimate relation with the rack of the register 50 bar.

The outer end of the locking bar 24 is threaded, as shown at 24^a, to receive the knurled head 24^b which, when secured to its proper position thereon, is locked by 75 said screw 24^c.

This provision of means for adjusting the head 24^b on the bar 24 not only facilitates the proper location of the coacting parts in the initial assemblage of the device but also 80 facilitates a readjustment which may be desired to compensate for slight wear of the camming surfaces.

It is thought that from the foregoing, the construction and arrangement of my register lock will be clearly understood, but I wish to reserve the right to effect such modifications of the illustrated structure as may come fairly within the scope of the protection 85 prayed.

What I claim is:—

1. The combination with a base formed to receive a supporting bar, of a locking bar movably mounted in the base and a camming device carried by the locking bar and 95 coacting with the base to urge the locking bar in one direction.

2. The combination with a base of a locking bar slidably mounted therein, a spring tending to urge the locking bar in one direction and a camming device for urging the bar in the opposite direction.

3. The combination with a base of a locking bar slidably mounted in the base, a spring tending to urge the locking bar from 105 its engaging position and a camming device operative to cam the locking bar in the opposite direction, whereby the spring will urge the locking bar from its engaging position, and whereby the camming device will 110 impart slight additional movement in the opposite direction to the locking bar after said bar has been moved to its engaging position in opposition to the spring.

4. The combination with a base and a locking bar slidably engaged, of a head carried by the locking bar and serving as a handle to slide the same to and from its engaging position, and a camming device operated by the head to cam the locking bar slightly 120 after the same has reached its engaging position.

5. The combination with a base and a locking bar slidably engaged, of a rotary camming device serving as a means for sliding the locking bar to and from its engaging position, and operative to cam the locking bar slightly when the same has reached its position of engagement.

6. The combination with a base, of a rack 130

- bar adapted to support the base, a rack block carried by the base to engage the rack bar, means for adjusting the rack block transversely of the base, and means carried 5 by the base and operative to draw the rack block into engagement with the rack bar.
7. The combination with a rack bar and base, of a rack block adjustably carried by the base, a locking bar also carried by the 10 base and engaging the rack bar, and means for camming the locking bar in one direction to draw the rack block into engagement with the rack bar.
8. The combination with a base and a locking bar slidably engaged, one of said members having a transversely disposed cam slot, of a rotary camming device carried by the other of said members, and movable in the cam slot to cam the locking bar to 20 its engaging position.
9. The combination with a base having a bar channel with parallel inclined side walls, of a supporting bar received by the bar channel and having oppositely inclined side 25 walls, and a locking bar movably carried by the base and having its engaging end inclined to conform to the adjacent side of the supporting bar, whereby the base will be rigidly retained on the supporting bar, 30 but may be lifted therefrom upon retraction of the locking bar.
10. The combination with a base, of a locking bar slidably mounted therein, a spring tending to move the locking bar longitudinally, and a camming device also operative to move the locking bar longitudinally. 35
11. The combination with a base having a cam slot, of a locking bar slidably mounted in the base, a spring tending to urge the locking bar in one direction, and a rotary element carried by the bar and having a wing coacting with the cam slot of the base 40 to urge the bar in the opposite direction.
12. The combination with a base provided
- with a channel for the reception of a bar, 45 of a rack block, and a locking bar mounted in the base at opposite sides of the channel.
13. The combination with a base and a bar having teeth, of a rack block mounted in the base to engage said teeth, and means 50 for effecting relative lateral adjustment of the rack block and base.
14. The combination with a base, of a rack block mounted therein, and adjustable retaining means for the block. 55
15. The combination with a base, of a rack block having trunnions, a pair of adjusting screws mounted in the base and engaging said trunnions, and a spring bearing on the rack block and tending to urge 60 the same toward its engaging position.
16. The combination with a base, of a locking bar carried thereby, a camming device for camming the locking bar to its engaging position, an operating head for said camming device, and means for locking the head 65 to the camming device.
17. The combination with a base, of a locking bar slidably mounted therein and a rotary member carried by the locking bar 70 and coacting with the locking bar and the base to urge the locking bar longitudinally when said member is rotated.
18. The combination with a base, of a locking bar slidably mounted therein, a rotary 75 member carried by the locking bar and coacting with the locking bar and the base to urge the locking bar longitudinally when said member is rotated, a head adjustable on the rotary member, and means for locking the head to the rotary member in the various positions of adjustment of said head.

In testimony whereof I affix my signature in presence of two witnesses.
